UNITED STATES PATENT OFFICE.

FREDERICK C. CRONIN AND JEROME A. HOFFMAN, OF DETROIT, MICHIGAN.

GRATE.

Application filed April 15, 1922. Serial No. 552,855.

To all whom it may concern:

Be it known that we, FREDERICK C. CRO-
NIN and JEROME A. HOFFMAN, citizens of
the United States of America, residing at
5 Detroit, in the county of Wayne and State
of Michigan, have invented certain new and
useful Improvements in Grates, of which
the following is a specification, reference be-
ing had therein to the accompanying draw-
10 ings.

This invention relates to grates for fur-
naces and hot fuel burning stoves, boilers
and other structures.

The primary object of our invention is
15 to furnish a furnace with a grate on which
very fine fuel may be burned and thus per-
mit of low grades of coal, as screenings or
mine wastes being used, without any danger
to the grate or furnace, and without produc-
20 ing any defects in a heating apparatus. This
is brought about by the manner in which air
is admitted to a fire bed to insure a thorough
combustion and an intense heat may be ob-
tained from such fine fuel thus permitting
25 of the furnace being economically operated.

Another object of this invention is to pro-
vide grate members by which air may be
distributed throughout a bed of fire or fuel
to insure thorough combustion and the man-
30 ner of admitting air to the fire chamber
tends to cool the grate and prevent warping
or disintegration due to an intense heat.

A further object of our invention is to
provide simple and durable members
35 through which air may pass to a combustion
chamber or fire box and a body of air is
maintained under the grate members, not
only for cooling purposes but in order that
the air may be preheated and thus placed
40 in a better condition for combustion pur-
poses.

A still further object of our invention is
to provide grate members that may be used
in connection with a furnace or heating ap-
45 paratus operated with a forced draft, and
the grate members are constructed so that
the air under pressure will be distributed in
the fuel and open up the fuel sufficiently to
permit of thorough combustion, there being
50 very little waste since an intense heat may
be maintained and all products of combus-
tion consumed before escaping to an exhaust
stack or chimney.

The above are a few of the objects at-
55 tained by our invention and others will here-
inafter appear as the construction is de-

scribed by aid of the accompanying draw-
ing, wherein—

Figure 1 is a longitudinal sectional view
of a furnace in accordance with our inven-
50 tion;

Fig. 2 is a horizontal sectional view of a
portion of the same;

Fig. 3 is a cross sectional view of a por-
tion of the furnace;

Fig. 4 is an enlarged detail sectional view
of a grate member showing air ports or jets
or twyers, and

Fig. 5 is a perspective view of a detached
grate member.

In the drawing, the reference numeral 1
denotes the greater portion of a furnace or
heating apparatus which includes a combus-
tion chamber or fire box 2 having a doorway
3 permitting of fuel being placed in the
75 combustion chamber 2 and clinkers or
ashes removed therefrom. In the bot-
tom of the furnace or heating apparatus is
a chamber 4 separated from the combustion
chamber 2 by a plurality of grate members
80 5 suitably mounted in the furnace to form
the bottom wall or floor of the combustion
chamber 2 and a ceiling or top wall of the
chamber 4.

Extending into the chamber 4 is an air
85 supply pipe 6 through which air may be
forced under pressure and said air supply
pipe is located adjacent a side wall of the
chamber 4 and is provided with air outlet
flared nozzles 7 adapted to direct air against
90 the lower faces of the grate members 5 or
heat disseminating ribs 8 and tubes 10 on
said grate members 5. The ribs 8 and tubes
10 constitute heat radiating fins and the air
contacting with the ribs, fins or tubes and
95 the bottom faces of the grate members 5 will
cool the grate members to a certain extent
and in so doing absorb heat from said grate
members and consequently be preheated.
The air supply pipe 6 and its nozzles may
100 supply sufficient air for the entire chamber,
depending on its size, or such a pipe may be
duplicated at the opposite side of the cham-
ber 4. In either instance it is to be under-
stood that there is sufficient air for the pur-
pose of our invention.

Each grate member may be rectangular,
round, square or any suitable shape in plan
and depending from the lower face of each
member are a plurality of air conduits 9
110 having lower bell shaped or flared ends 10
permitting of air easily entering said con-

duits and since the conduits are carried by the grate member heat will be radiated thereby and air entering the conduits heated and placed in a better condition for combustion purposes.

The upper end of each conduit communicates with diverging or angularly disposed air outlet ports or jets or twyers 11 opening at the upper face of the member 5, it being preferable to circumferentially arrange or cluster the open ends of the ports or jets or twyers 11, as best shown in Fig. 5. The angularity of the ports or jets depends on the nature of fuel to be burned on the grate member and also upon the height and area of the combustion space above the grate and thickness of the fire bed to be maintained. For instance, if a fire bed of known depth is to be maintained in the combustion chamber the ports or jets or twyers 11 can be disposed at such angles that the ports or jets or twyers of one conduit will discharge currents of air that will intersect currents of air emitted by other or adjacent ports or jets or twyers with the inner section of said currents of air occurring at the top or surface of the fire bed. In this manner air will be supplied throughout the fire bed for combustion purposes, and it will be possible to burn a high percentage of the fuel placed on the grate members. When the fuel is in a finely divided condition the currents of air injected in the fuel will tend to open up the fuel to such an extent that all particles thereof will be either burned or subjected to an intense heat and there is no danger of any fuel packing or lying dormant on the grate members. In other words, a live bed of fuel will be maintained and an intense heat obtained therefrom.

Since air will be ejected from the ports or jets or twyers 11 there is no danger of firmly powdered fuel clogging ports or jets or twyers, and it is apparent that the grate members may be made with the air outlet ports or jets or twyers so disposed as to produce the best results in connection with a solid fuel burning furnace or heating apparatus.

While in the drawing there is illustrated a preferred embodiment of our invention, it is to be understood that the construction is susceptible to such changes as are permissible by the appended claims.

What we claim is:—

1. As a new article of manufacture, a fuel supporting grate member having a relatively thick wall provided with a group of diverging openings having the lower ends thereof terminating between the upper and lower faces of said member, and a relatively

thin wall air inlet conduit solely supported by its upper end fitting in the lower face of said grate member in communication with the lower ends of the diverging openings of 65 said member.

2. Means adapted to induce a draft below and through a grate, comprising a grate member having groups of diverging openings therein with the lower ends of said 70 openings terminating in a plane between the upper and lower faces of said member, and a relatively thin wall conduit having its upper end mounted in the lower face of said member and communicating with the lower 75 ends of said diverging openings so that air may circulate about said conduit and pass through said conduit and grate member.

3. In a heating apparatus, grate members, a chamber above said grate members 80 in which a fire may be maintained, a chamber below said grate members adapted to receive air, depending conduits carried by said grate members within the air receiving chamber, said grate members having openings therein communicating with said conduits and adapted to supply air to the fire chamber, and an air supply pipe extending into the air chamber and adapted to direct air upwardly against the lower faces of the 90 grate members.

4. In a heating apparatus, a fire chamber, an air receiving chamber, grate members separating said chambers, said grate members having groups of diverging openings 95 therein adapted to distribute air in a fire bed in the fire chamber, air heating conduits carried by said grate members and communicating with the openings thereof and extending into the air chamber, an air supply pipe adapted to supply air to said air chamber, and nozzles carried by said air supply pipe and adapted to direct the air against said grate members and the conduits carried thereby.

5. As a new article of manufacture, a fuel supporting grate member having a relatively thick wall, provided with openings having the lower ends thereof terminating between the upper and lower faces of said 110 member, and a bell-mouthed air inlet conduit solely supported by its upper end fitting in the lower face of said grate member, in communication with the lower ends of the openings of said member.

In testimony whereof we affix our signatures in presence of two witnesses.

FREDERICK C. CRONIN.
JEROME A. HOFFMAN.
